UNITED STATES PATENT OFFICE.

HENRY ANTON BOCK, OF MILFORD, CONNECTICUT.

CIGAR AND METHOD OF BLENDING THE SAME.

Specification of Letters Patent.

Patented Apr. 24, 1917.

1,223,362.

Application filed May 25, 1916. Serial No. 99,725.

To all whom it may concern:

Be it known that I, HENRY ANTON BOCK, a citizen of the United States of America, and a resident of Milford, county of New Haven, State of Connecticut, have invented certain new and useful Improvements in Cigars and Methods of Blending the Same, of which the following is a specification.

This invention has reference to improvements in cigars and the method of blending the same.

Cigars usually found in the market contain a filler, a binder and a wrapper. The filler generally consists of one kind of tobacco of various qualities according to the price of the cigar.

It has been found that cigars, especially those of the middle grades are not as agreeable a smoke and do not burn as nicely as desired if the filler is composed of one kind of tobacco. In order to obtain the maximum of odor and flavor of a cigar it is desirable to mix various kinds of tobacco for the filler or as it is called to blend the same.

It is a difficult matter, in the ordinary course of manufacturing cigars, to thoroughly mix or blend the various kinds of tobacco, on account of the similarity of the leaves, and the operator cannot be relied upon when the leaves are mixed in bulk to get the required blend in every bunch. Under the old style or method of making cigars the various kinds of tobacco, constituting the blend, for the respective cigars to be made were mostly or invariably mixed in bulk and to give a cigar maker more than three or four different kinds of tobacco to be put into one cigar makes it awkward for him to work. Further it occasionally happens that the various leaves are too closely pressed together in using this method which thus endangers the free drawing of the cigar.

The described deficiencies are avoided in the novel method of blending cigars and in the resulting product. The novel method enables the operator to thoroughly blend and mix various kinds of tobacco in such a way that they are evenly and uniformly distributed in one cigar whereby the burning of the same and the taste and aroma as well as its smoking quality are greatly improved. By arranging the various kinds of tobacco and bringing them together according to my new and improved method of blending a better and more uniform burning or combus-

tion is effected and a better cigar obtained with improved taste, flavor and aroma. This has been primarily attained by producing separately individual little rolls of each kind of tobacco which may be made by different operators and uniting a plurality of the various little rolls by means of a binder into a so called bunch which then is covered by a wrapper in the usual manner to complete the cigar. As these individual little rolls are uniformly made a possible twisting of the various kinds of tobacco is prevented when a plurality of the various little rolls is formed into a bunch. The twisting occasionally happens when the old method is used. It impairs the free drawing of the cigar and causes an irregular burn. It is evident that a more freely drawing article is obtained by the described method because each individual little roll forms in itself an independent part of the bunch within the cigar. The plurality of little rolls do not form an integral filler but rather a perfectly blended compound filler.

In order to render the invention entirely clear reference is had to the accompanying drawing in which:

Figure 1 represents in perspective view an individual little roll of tobacco.

Fig. 2 illustrates in perspective view a plurality of assembled little rolls each made of a different kind of tobacco.

Fig. 3 shows a plurality of such assembled little rolls on a binder ready to be rolled up therein to form a blended bunch.

Fig. 4 illustrates the blended finished cigar with the wrapper around the same.

Similar characters of reference denote like parts in all the figures.

In the drawing in Fig. 1 a single thin little roll of tobacco is shown in perspective view. This little roll *a* is made of one kind of tobacco while another kind of little rolls is separately made of another kind of tobacco and so forth, each kind preferably by a different operator who thus cannot make a mistake. A plurality of such little rolls, each composed of a special kind of tobacco is assembled as shown in Fig. 2 wherein four little rolls, *b*, *c*, *d*, *e*, are represented. Such a plurality of little rolls, when assembled, is placed upon a binder as shown in Fig. 3 wherein six thin little rolls, *f*, *g*, *h*, *i*, *j*, *k*, are shown resting on the binder *l*. The plurality of thin little rolls then is rolled up into the binder to form a bunch which then

contains various kinds of tobacco with their various characteristic properties as to flavor, taste and aroma. Each bunch so formed is then surrounded by a wrapper *m* in the usual manner for the purpose of completing the cigar.

In the described manner three, four, five and even more little rolls, each composed of a different kind (or quality) of tobacco may 10 be assembled to form a bunch, usually by means of one binding leaf. However if desired two or more binding leaves may be employed to form the bunch with the thin little rolls. The assembled thin little rolls may 15 be formed into any desired shape of cigar. In Fig. 4 of the drawing a cigar of the so called perfecto shape is shown for example.

In the described manner an improved blended cigar is produced as to flavor, taste 20 and aroma as well as to uniform burning and drawing during smoking the cigar. At the same time the method of blending the cigars has been improved and simplified and mistakes in blending the various kinds of 25 tobacco during manufacture are prevented.

I claim as my invention:

1. As a novel article of manufacture a

blended cigar having a compound filler composed of a plurality of thin rolls, each of said rolls being made of one kind or quality 30 of tobacco and at least one of which rolls is made of a different kind or quality of tobacco from at least one other of said rolls, said rolls being assembled within a wrapper and in the shape of a cigar.

2. A process of manufacturing blended cigars which comprises separately preparing thin rolls each composed of a single kind or quality of tobacco, selecting a number of such rolls, including a plurality of kinds or 40 qualities of tobacco, said number of rolls being sufficient in amount to form the filler of a cigar, and assembling the same substantially parallel to one another to form the filler of a cigar, and thereafter completing 45 the manufacture in the usual manner by the application of the wrapper structure.

Signed at New York, N. Y., this 23rd day of May, 1916.

HENRY ANTON BOCK.
